UNITED STATES PATENT OFFICE

157,330

TRAILER BODY

James J. Black, Cincinnati, Ohio, assignor to The Trailmobile Company, Cincinnati, Ohio, a corporation of Ohio

Application July 2, 1948, Serial No. 147,350

Term of patent 14 years

(Cl. D14—3)

To all whom it may concern:

Be it known that I, James J. Black, a citizen of the United States, residing at Cincinnati, in the county of Hamilton and State of Ohio, have invented a new, original, and ornamental Design for a Trailer Body, of which the following is a specification, reference being had to the accompanying drawings, forming a part thereof.

Figure 1 is a perspective view showing the rear end and one side of a trailer body incorporating the new design.

prise the appearance of the rear end portion of the trailer body, as illustrated in full lines.

I claim:

The ornamental design for a trailer body, substantially as shown and described.

JAMES J. BLACK.
